UNITED STATES PATENT OFFICE.

JOHN WAHL AND OTTO MELZER, OF BOROUGH OF QUEENS, NEW YORK, ASSIGNORS TO
A. SCHRADER'S SON, INC., OF BROOKLYN, NEW YORK, A CORPORATION OF NEW YORK.

TUBE-DEFLATING MACHINE.

Application filed November 24, 1926. Serial No. 150,504.

This invention relates to improvements in pneumatic tube deflating machines and aims to simplify and increase the efficiency of such devices.

Heretofore it has been usual to deflate pneumatic tubes by connecting the valve stem of the tube with an operating vacuum pump and to employ mechanical means of one form or another in engagement with or 10 in proximity to the foot of the valve stem to maintain the walls of the tube separated at the point whereat the air is exhausted until substantially all the air has been evacuated from the tube. In most of these processes the tube, after deflation, does not lie flat nor conveniently lend itself to rolling or folding for packing without buckling. This is particularly true of tire tubes which are formed on curved mandrels. 15 According to the present invention we provide a novel arrangement of tube support which dispenses with all forms of mechanical means for holding the tube walls spaced from the foot of the valve stem, and have 20 found that all that is required to insure that the tube will be efficiently deflated, and that when so deflated it will lie substantially flat and be free from buckling when rolled or folded, is to place the tube on the support 25 and connect the tube valve stem to the operating vacuum pump. Briefly stated, we accomplish these results by supporting the tube to be deflated over a supporting frame in such co-operative relation that the tube upon deflation will, due to the action of gravity thereon assume a substantially flat arcuate form and have its walls adjacent the foot of the tube valve stem maintained spaced away 30 from the opening through said foot portion. The tube in this condition can be quickly removed from the support and folded or rolled for packing. The invention also includes other features of novelty which will be hereinafter more fully described. 35 A preferred embodiment of our invention is illustrated in the accompanying drawings wherein,

Figure 1 is a fractional elevation of our tube deflating machine with parts thereof being shown in section.

Fig. 2 is a top plan view of Fig. 1.

Fig. 3 is a longitudinal section of an improved coupling used with our invention.

Referring to the drawings A indicates a base upon which is mounted a vertical up-

right or standard B formed at its top with a hollow bearing C having an external circumferential groove c which communicates with the hollow interior of the bearing through openings c'. Connected to the top of the interior of the bearing C is a tube D communicating with a suction pump (not shown). 60

Rotatably mounted upon the bearing C is a movable carrier E having a plurality of radial ducts e communicating with the interior of the bearing C through the groove c and opening c'. The carrier E carries a plurality of supporting arms F, each of which is preferably in the form of a rigid tube communicating with a duct e in the carrier E. Said supporting arms F are preferably horizontally disposed and include an angularly disposed portion f, the free end of which is closed by a plug f' or the like, said portion f preferably forming approximately 75 a right angle with the horizontal arm F. Dependently supported by said arms F and preferably in communication therewith is a flexible conduit G, which, at its free end, carries a coupling device indicated as a whole 80 by the letter H, said coupling being intended for quick attachable and detachable engagement with the end of a tube valve stem attached to the tube to be deflated.

The coupling H consists of a housing J 85 having a bore therethrough within which is axially movable a tubular member K, one end k of which is formed for engagement with the conduit G, and the other end k' of which is designed for engagement with 90 a tire valve stem. Within the end k' of the tubular member there is mounted a disk packing L, upon which seats a disk valve M provided on one side with a depending tire valve unseating pin m, and on its opposite side with a guiding stud m', which stud has a lateral passage m² adapted to establish communication between opposite ends of the tubular member when the valve M therein is unseated. The valve M is maintained normally seated on the packing L by a spring m³, the tension of which is slightly greater than the suction effect operating to unseat the valve M. Pivotaly mounted upon the housing J are a pair of arms N, the lower 100 ends of which carry a pair of jaws n which are normally urged into inward or engaging position by coil springs n' positioned between the housing and said arms, said jaws n being movable outwardly by pressing the 105

arms N together. Between a shoulder within in the housing J and a shoulder on the member K there is positioned a coil spring O normally urging the member K toward the tire valve engaging end of the coupling, said member K being limited in said movement by engagement with the jaws n. The function of said spring O is to insure a leak-tight joint between the packing L and the top of a tire valve stem when the coupling is attached thereto. The housing J is also adapted for free rotation on the tubular member K and is limited in its outward movement on the member K by a split spring j mounted on the member K.

In the operation of the device two operators are preferably employed, the duty of the first being to mount the tire to be deflated upon the supports, and the duty of the second to merely remove the deflated tires from the supports when they reach him, the rate at which the tubes are deflated being controlled so that a tire will be completely deflated in the rotation of the carrier member E from the first operator to the second. Specifically, the deflating operation is carried out as follows: The first operator will first connect coupling H to the valve Q of the pneumatic tube P to be deflated, thereby simultaneously unseating the valve within the valve stem and the valve M within the coupling, thereby establishing fluid communication between the interior of the tube P and the suction pump. The tube P is then mounted upon the support with portions p and p' thereof disposed on opposite sides of the support, as best shown in dotted lines in Figs. 1 and 2. When so positioned, the tube is sent on its circuit around the bearing C by being either given a gentle push by the operator or by mechanical means for rotating the carrier E at a predetermined rate. The mounting of the tubes P is continued by the first operator, and as deflation progresses, the portions of the tubes on opposite sides of the support will fall and assume arcuate forms which will have a substantially flat condition, as best shown in full lines in Figs. 1 and 2; by the time said tubes reach the second operator, whereat said tubes are removed from the support. The initial mounting of the tube upon a support and the connection between the coupling and the tube valve stem is preferably such that the tube valve stem will have a relation to the walls of the tube adjacent the foot portion of said valve stem, such that upon deflation of the tube the action of gravity upon said tube walls will maintain said walls spaced away from or out of engagement with the opening through the foot of the valve stem, and we have found that when the relationship of parts is as outlined no auxiliary spreader devices, either mechanical or otherwise, need be em-

ployed for maintaining the walls of the tube spaced from the foot of the valve stem so as to permit complete evacuation of the tube. It will be accordingly understood that because of this, greater efficiency in deflation of tubes can be realized. Also, because of the fact that the tubes in deflated condition will assume the substantially arcuate flat formation as shown in the drawings, tubes deflated according to the present method and on the structure of the present device are peculiarly better adapted for folding or rolling, when packing the tubes for market. We have found that all pneumatic tubes, whether formed on straight or curved mandrels, can be equally well deflated according to the present invention.

While we have shown and described a preferred embodiment of our invention we wish it to be understood that changes in structural details may be resorted to without departing from the spirit of the invention.

What we claim is:

1. A pneumatic tube deflating mechanism comprising a support having angularly-disposed portions upon which a pneumatic tube to be deflated can be placed, which tube, when so positioned, will have portions thereof disposed on opposite sides of the plane of the support with its valve stem free to move as the tube is being deflated, and means connecting with a suction device for engaging the end of the tube valve stem, the co-operative relation of the tube valve stem, support and means connecting with the suction device being such that the tube, upon deflation, will, due to the action of gravity thereon, have its walls adjacent the foot of the tube valve stem maintained spaced away from the opening through the foot of the valve stem.

2. A pneumatic tube deflating mechanism which is free from mechanical means for holding the tube walls spaced from the foot of the valve stem comprising a support upon which a tube to be deflated can be supported with the foot of the tube valve stem below the point of support, and means connecting with a suction device for engaging the end of the tube valve stem to exhaust the air from the tube, the co-operative relation of the tube valve stem, support and means for connecting with the suction device, when a tube is mounted on the support being such that the tube upon deflation will, due to the action of gravity thereon, have its walls adjacent the foot of the tube valve stem maintained spaced away from the opening through the foot of the valve stem.

3. A pneumatic tube deflating mechanism which is free from mechanical means for holding the tube walls spaced away from the foot of the valve stem comprising a support upon which a tube to be deflated can

be supported in such manner that the tube valve stem will be free to move as the tube is being deflated, and such that upon deflation, the tube will assume an arcuate substantially flat form with the tube valve stem axis lying within the planes of the flattened walls of the deflated tube.

4. A pneumatic tube deflating mechanism comprising a support upon which a pneumatic tube to be deflated can be placed, which tube when so positioned will have portions thereof disposed on opposite sides of the plane of the support and its valve stem free to move as the tube is being deflated, and means connecting with a suction device for engaging the end of the tube valve stem to exhaust the air from the tube, said support being such that upon deflation of said tube, the portions thereof disposed on opposite sides of the support will fall on said opposite sides of said support and assume a substantially flat condition.

5. A pneumatic tube deflating mechanism comprising a support having angularly disposed portions upon which a pneumatic tube to be deflated can be placed, which tube when so positioned will have portions thereof disposed on opposite sides of the plane of the support with its valve stem free to move as the tube is being deflated, and means connecting with a suction device for engaging the end of the tube valve stem, said support being such that upon deflation of said tube, the portions thereof disposed on opposite sides of the support will droop down over said opposite sides of said support and assume arcuate forms which will have a substantially flat condition between said angularly-disposed portions of the support.

6. A pneumatic tube deflating mechanism comprising a support having portions thereof disposed substantially in a common plane at an angle to each other over which a pneumatic tube to be deflated can be placed, which tube when so positioned will have portions thereof disposed on opposite sides of the plane of the support, and means connecting with a suction device for engaging the end of the tube valve stem, said support being such that upon deflation of said tube, the portions thereof disposed on opposite sides of the support will droop down over said opposite sides of said support and assume arcuate forms which will have a substantially flat condition and be parallel with each other.

7. A pneumatic tube deflating mechanism comprising a support having portions thereof disposed substantially in a common plane at a right angle to each other upon which a pneumatic tube to be deflated can be placed, which tube when so positioned will have portions thereof disposed on opposite sides of the plane of the support, and means connecting with a suction device for engaging

the end of the tube valve stem, said support being such that upon deflation of said tube, the portions thereof disposed on opposite sides of the support will droop down over said opposite sides of said support and assume the form of arcs of approximately 90°, which arcuate portions will lie in substantially flat coincident relation.

8. A pneumatic tube deflating mechanism comprising a support having a substantially horizontally disposed member, means connecting with a suction device, a coupling for engaging the end of a pneumatic tube valve stem, said coupling being connected to said means by a flexible conduit, said horizontal member being adapted to support a pneumatic tube to be deflated, which tube when so supported will have portions thereof disposed on opposite sides of said horizontal member with the tube valve casing free for engagement with said coupling and free to move as the tube is being deflated, the arrangement of the parts being such that upon deflation of said tube, the portions thereof disposed on opposite sides of the horizontal member will gradually droop down over said member, until upon substantially complete evacuation of the tube, said portions thereof on opposite sides of the horizontal member will assume a substantially flat condition.

9. A pneumatic tube deflating mechanism according to claim 8, wherein the horizontally disposed member is in the form of a rigid conduit which is connected with the suction device, and wherein the flexible conduit is dependently supported from said rigid conduit and in communication therewith.

10. A pneumatic tube deflating mechanism which is free from mechanical means for holding the tube walls spaced from the foot of the valve stem, comprising a support upon which a tube to be deflated can be supported in such manner that the tube valve stem will be free to move as the tube is being deflated, means connecting with a suction device for engaging the end of the tube valve stem to exhaust the air from the tube, the co-operative relation between the tube valve stem, the support and means connecting with the suction device when a tube is mounted on the support being such that the tube, upon deflation, will, due to the action of gravity thereon, have its walls adjacent the foot of the tube valve stem maintained spaced away from the opening through the foot of the valve stem to permit substantially complete evacuation of the tube.

11. The method of deflating pneumatic tubes that comprises mounting a tube to be deflated upon supporting means so that the foot of the tube valve stem and the tube walls adjacent said valve stem will lie below said supporting means whereby upon de-

24
flation of the tube, the action of gravity on said tube walls adjacent the foot of the tube valve stem will maintain said walls spaced away from the opening through said valve 5 stem foot, and connecting said valve stem with a suction device to exhaust the air from the tire.

12. The method of deflating pneumatic tubes, that comprises supporting a tube to 10 be deflated at substantially diametrically opposed points upon supporting means so

that portions of the tube will be laterally disposed on opposite sides of the supporting means, leaving said laterally disposed portions unsupported and free to fall down- 15 wardly as the tube is being deflated, and connecting said valve stem with a suction device to exhaust the air from the tube.

In witness whereof, we have hereunto signed our names.

JOHN WAHL.
OTTO MELZER.
